UNITED STATES PATENT OFFICE

2,661,954

AMUSEMENT AND TARGET PRACTICING
DEVICEJerry C. Koci, Barrington, Ill., assignor to Chicago
Coin Machine Co., Chicago, Ill., a corporation
of Illinois

Application July 14, 1953, Serial No. 367,805

5 Claims. (Cl. 273—101.2)

1

The invention has for one of its principal objects the provision of a simple and easily operated control member arranged adjacent a seat within a movable cockpit so that by proper manipulation the cockpit may be moved horizontally and/or vertically about a fixed center point.

Another object of the invention is to provide a target and score registering board having target elements thereon, at which targets the entire movable cockpit must be aimed to register a score.

Still another and equally important object of my invention is the provision in a device of this character of an arrangement whereby a movable vehicle body has mounted thereon a simulated gun, which, together with the vehicle body, is adapted to be aimed at target elements on a stationary target board.

Still another important object of my invention is the provision of a simple arrangement of parts that will complete an electric circuit to light certain target elements when said movable vehicle body and said gun are synchronized in a direct line with respect to the target elements.

Still another and equally important object of my invention is to provide a simple and efficient pneumatic means for moving a simulated vehicle cockpit horizontally and vertically about a fixed point.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of my invention, together with a target and score registering board;

Fig. 2 is a fragmentary side view of the mounting for the simulated vehicle cockpit embodied in my invention, taken substantially on line 2—2 of Fig. 3;

Fig. 3 is a fragmentary sectional view taken on line 3—3 of Fig. 2;

Fig. 4 is a vertical sectional view of the support for the simulated vehicle body;

Fig. 5 is a sectional detail view taken substantially on line 5—5 of Fig. 2;

Fig. 6 is a fragmentary sectional view showing the interior of the enclosed nose portion of the simulated vehicle cockpit;

Fig. 7 is a sectional detail view taken on line 7—7 of Fig. 2;

Fig. 8 is a fragmentary end view of the support for my simulated vehicle cockpit taken substantially on line 8—8 of Fig. 2;

2

Fig. 9 is a top plan view of the operating mechanism as employed in my invention, taken substantially on line 9—9 of Fig. 6;

Fig. 10 is a sectional detail view taken substantially on line 10—10 of Fig. 9;

Fig. 11 is a schematic detail view of the electric circuit as embodied in my invention; and

Fig. 12 is a schematic detail view of an electric and pneumatic circuit as embodied in my invention.

In Fig. 1 a movable simulated vehicle cockpit is indicated at 10. This cockpit comprises a seat member 11, a backrest 12 and an enclosed nose portion 13. Fixedly secured and carried atop the nose portion 13 is a simulated gun 14.

A target or score registering board 15 is adapted to be associated with my device as shown in Fig. 1, wherein such target and score registering board 15 is positioned in front of and at right angles to the cockpit 10 and is supported by legs 17 attached to the platform 18 of the vehicle cockpit 10. This target board 15 may be provided with a plurality of target elements 16, as shown in Fig. 1. In the present instance, these elements 16 are lights adapted to be illuminated by the proper synchronization of a line of sight between the gun 14 and the lights in a herein-after described manner. The cockpit 10 is supported from the platform 18 by a hollow pedestal 19, which pedestal has a base portion 20 which is secured to the platform 18 in any suitable manner, such as by screws 21. One end of the hollow pedestal 19 is closed by a reduced bearing 22 frictionally fitted therein. To the top of the reduced bearing 22 is attached a bearing plate 23 provided with a pair of bearing blocks 24, each having a corresponding bearing cap 25, which is adapted to be attached to the bearing blocks 24 in any suitable manner, such as by screws 26, as shown in Figs. 2 and 4. These bearing blocks 24, as well as the bearing caps 25, are provided with semi-circular cut-out portions 24' and 25' respectively and are so arranged that when the caps 25 are secured to the blocks 24, these cut-out portions 25' and 24' respectively, will form a circular bore.

Pivotedly journaled in this circular bore is a supporting rod 27. This rod 27 extends upon the bearing blocks 24, as shown in Figs. 2, 4 and 8, and has its end portions journaled through a pair of spaced apart parallelly extending angle irons 28 beneath the floor board 29 of the cockpit 10.

In the above-described manner, and from the specific arrangement of parts, it is readily seen that the cockpit 10 is supported on the pedestal 19 for pivotal movement around the long axis of

the supporting rod 27. Such pivotal movement is accomplished in the hereinafter described manner.

The bearing plate 23 has extending downwardly therefrom through the reduced bearing 22 and within the hollow pedestal 19 a shaft 30. This shaft 30 extends below the base 20 of the pedestal 19 and projects through an aperture 31 formed in the platform 18, as shown in Fig. 4. The lower free end of the shaft 30 has fixedly secured thereto an arm 32 which extends laterally with respect to the long axis of the shaft 30. One end 33 of this arm 32 is pivotally connected to a link 34. The link 34 has at its free end an enlarged head 35 which is provided with a threaded bore 36. Into this bore 36 is threaded one end of a piston rod 37. A lock nut 38 carried by the piston rod 37 is employed to lock the rod 37 in the bore 36, as viewed in Fig. 5. This piston rod 37 forms an actuating part of an air cylinder 39, which is pivotally carried beneath the platform 18. This cylinder 39 is secured to the platform 18 by a bracket 40 which is provided with a depending arm 41 to which the free end 42 of the cylinder 39 is attached.

On one side of the pedestal 19 and formed integral therewith is a pair of laterally extending bracket arms 43. These brackets 43 are provided with a vertically extending bore 44, through which a suitable lock pin 45 is adapted to be disposed. Between these brackets 43 is a link 46 which has a corresponding bore 47 which will receive the lock pin 45 so as to fixedly secure the link 46 between the brackets 43. The free end of this link 46 is pivotally connected to a piston rod 48 of a second air cylinder 50, as viewed in Fig. 2. This air cylinder 50 is pivotally connected to the floor board 29 in a manner much like the cylinder 39 is connected to the platform 18.

The two air cylinders 39 and 50 are connected through suitable hose connections 51 to an air compressor 52 carried by the forwardly extending portions 53 of the angle irons 28 within the nose portion 13 of the cockpit 10, as viewed in Fig. 7.

From the foregoing described arrangement of parts, it is readily apparent that through the action of the air cylinders 39 and 50 acting upon the shaft 30 and the piston rod 48 respectively, the cockpit 10 is pneumatically pivotable around the supporting pedestal 19.

Within the nose portion 13 of the cockpit 10 is a compartment 54. This compartment is formed by a bottom wall 55 supported off the floor board 29 of the cockpit 10 by angle irons 56 and which angle irons 56 extend upwardly from the supporting angle irons 28. Into this compartment 54 is slidably fitted a drawer 58 which is made up of side walls 59 and 59', a bottom wall 60, and a face plate 61. This face plate 61 is provided with side flanges 62 by which the drawer 58 is securely fastened within the compartment 54. The rear portion of the bottom wall 60, adjacent its end thereof, provides a partially vertical partition 63 having a circular aperture 64 formed therein. The face plate 61 is provided with a corresponding aperture 65. Slidably journaled through the aperture 63 of the face plate 61 and the aperture 64 of the partition 63, and extending throughout the length of the drawer 58, is a shaft 66.

The outer free end of this shaft 66 is provided with an operating lever 67, which in this case is a simulated semicircular steering wheel 67.

The shaft 66 is slidably held within the drawer 58 by supporting brackets 69 and 70 which are carried by the bottom wall 60 of the drawer 58. To the rear of the bracket 69 the shaft 66 is provided with a reduced portion 71, which extends to the end of the shaft 66. Such reduced portion 71 provides a shoulder 72. Slidably journaled on the shaft 66 adjacent the shoulder 72 is a washer 73 provided with a sleeve 74 extending rearwardly therefrom. Adjacent the rear end 75 of the shaft 66 is journaled a stop washer 76 secured to the shaft 66 by a cotter pin 77. This stop washer 76 is of a diameter slightly smaller than the aperture 64 of the partition 63 through which the shaft 66 is journaled. Immediately forward of this stop washer 76 is a corresponding washer 78 having a like sleeve 79 which extends forwardly with respect to the stop washer 76. These washers 73 and 78 and corresponding sleeves 74 and 79 are freely slidable on the shaft 66 and are separated from each other by an expansion spring 80 as viewed in Fig. 9.

Adjacent the bracket 69 and on either side of the shaft 66 are micro switches 81 and 82. These switches 81 and 82 are provided with contact leaves 81' and 82' respectively. One end of each of these contact leaves 81' and 82' is provided with rollers 83 and 83'. These rollers 83 and 83' are positioned to bear upon the washers 73 and 78 respectively. The opposite ends of these contact leaves 81' and 82' are held in a spaced apart relation with respect to contacts of the micro switches 81 and 82 by a spring arrangement (not shown).

The operation of these switches 81 and 82 are as follows:

The shaft 66 when pushed inwardly of the drawer 58 will slide through the brackets 69 and 70 and will cause the shoulder 72 to bear upon the washer 73, thus compressing the spring 80. The rearward movement of the shaft 66 together with the washer 73 will permit the roller 83 of the spring leaf 81' to roll off the edge of the washer 73 thus permitting a contact to be made by the opposite end of the leaf 81' within the micro switch 81. In reversing the procedure when the shaft 66 is withdrawn from within the drawer 58, the stop washer 76 will pass through the aperture 64 of the partition 63 and will engage the washer 78 and will slide the same forward in the direction of the face plate 61. The movement of the washer 78 will permit the roller 83' to roll off the edge thereof thus permitting the leaf 82' to make contact within the switch 82. It should be noted that as the washers 73 and 78 are freely slidable on the shaft 66 they are restrained from moving in both directions. The washer 73 when the shaft 66 is withdrawn from the drawer 58 will bear upon the bracket 70 and be prevented from movement in that direction. The washer 78 will bear upon the partition 63 when the shaft 66 is pushed inwardly of the drawer 58 and thus be prevented from moving in a corresponding direction.

From the foregoing, it is readily apparent that the switch 81 may be actuated while the switch 82 remains inoperative, the same being true in reverse.

Positioned within the drawer 58 and between the brackets 69 and 70 and extending upwardly from the side walls 59 and 59' are supporting arms 84 and 85. These supporting arms 84 and 85 are attached to the side walls 59 and 59' in any suitable manner such as by screws 86 as

shown in Fig. 10. At the base of these supporting arms 84 and 85 and within the side walls 59 and 59' and attached by the same screws 86 are a second pair of micro switches 87 and 88. These switches 87 and 88 have spring-urged contact leaves positioned at the top thereof.

On the shaft 66 in approximately the same plane as the switches 87 and 88 there is fastened an actuating bar 89. This actuating bar 89 is provided with vertical wings 90 and 91, which terminate into fingers 90' and 91'. These fingers 90' and 91' extend in an upward and outward direction with respect to each other, as shown in Fig. 10. The upper end portion of the supporting arms 84 and 85 is provided with inwardly extending supporting fingers 92 and 92', which are attached to the fingers 90' and 91' by springs 93 and 94. With this arrangement of parts the actuating bar 89, although fixedly attached to the shaft 66 is provided with wings 90 and 91 which are rotatable to a limited degree upon rotation of the shaft 66. For example, when the shaft 66 is rotated in a clockwise direction, the wing 90 will move in a corresponding direction against the action of the spring 93. The wing 90 will rotate until the finger 90' thereof comes into contact with the leaf of the micro switch 87. The same is true of the wing 91, the finger 91', the leaf of the switch 88. The purpose and function of individually making contact through the switches 87 and 88, as well as the switches 81 and 82, will be hereinafter described.

To rotate the vehicle cockpit 10 horizontally about the pedestal 18, the following operation takes place:

The operator of the device will, by turning the steering wheel 67, rotate the shaft 66, thus causing the actuating bar 89 to turn therewith. The turning of the actuating bar 89 will cause the micro switch 87 or 88 to be closed.

The micro switches 87 and 88 are connected in circuit to electromagnetic actuating valves #3 and #4 respectively through conductors 95. The other side of these switches are connected through conductors 96 to a power source 97. These valves #3 and #4 control the passage of compressed air from the compressor 52 to the air cylinder 39. These valves are of standard construction and make up no part of the invention. The valve #3 which is actuated by the closing of the switch 87 permits compressed air to pass from the compressor 52 through the hose 51 to the cylinder 39, which compressed air will force the piston rod 37 outwardly of the cylinder 39. The valve #4 is connected by conductors 95 to the micro switch 88. When this micro switch 88 is closed the valve #4 permits the compressed air to enter the cylinder 50 to force the rod 37 back in the cylinder. By such movement of the rod 37, being forced in or out of the cylinder 39, the cockpit 10 is rotated about the pedestal 18.

For the operator to effect an up and down movement of the cockpit nose 13, the steering wheel 67 will be pushed inwardly of the compartment 54 to bring the nose down, or the steering wheel will be pulled outwardly of the compartment to pull the nose up. Such movement of the wheel 67 will impart movement to the shaft 66 which will permit the closing of the micro switches 81 or 82. For example, say the operator wishes to lower the nose of the cockpit 10. The operator would push upon the wheel 67 sliding the shaft 66 inwardly of the compartment 54. This movement of the shaft 66 would cause the roller

83 to ride off the washer 78, thus permitting the contact leaf 81' to make contact within the switch 81. The switch 81 is connected through conductors 98 to valve #1, thus opening the valve #1 and permitting compressed air to be admitted from the compressor 52 through the hose 51. This compressed air will force the rod 48 inward of the cylinder 50 and thus, through the link 46, by which the cylinder 50 is connected to the pedestal 19, the cockpit nose will be forced down.

In reversing the operation, if the operator desires to raise the nose of the cockpit 10, the steering wheel 67 will be pulled outwardly of the compartment 54. This movement will cause the shaft 66 to slide outwardly of the compartment 54. Upon movement of the shaft 66, the roller 83' will ride off the washer 78, thus permitting the contact leaf 82' to make contact within the switch 82. This switch 82 is connected through conductors 98 to valve #2 and upon the making of contact within the switch 82, the valve #2 will be opened permitting the compressed air to be admitted into the cylinder 50. The compressed air will force the rod 48 out of the cylinder 50, thus pivoting the vehicle cockpit 10 about the shaft 30.

From the foregoing, it is apparent that the horizontal and vertical movement of the vehicle cockpit 10 is completely controlled by the manual manipulation of the steering wheel 67.

As aforementioned, associated with the movable vehicle cockpit 10, is a score registering board 15. This board 15 may be provided with target elements 16. These elements may be lights adapted to be illuminated upon proper completion of an electrical circuit. These target elements 16 are shown in Fig. 1, are depicted as being located on a map of the continents of the world with each element thereof being positioned in various scattered points thereon. These target elements 16 are consecutively numbered and are adapted to be successively illuminated. These target elements 16 are arranged in the electrical circuit as shown in Fig. 11. The elements 16, at one side thereof, are connected through conductors 99 to a power source 97. The other side of the target elements 16 are connected through conductors 100 to a plurality of holding relays 101, which relays 101 will be energized by the completion of the electrical circuit to the target elements 16.

To energize the target elements 16, as contained on the target board 15, the device is provided with a novel combination of parts which performs this function and complete an electric circuit upon the proper manipulation of the movable vehicle cockpit 10 and upon creating a direct line of sight between the simulated gun 14 carried by the cockpit 10 and the target elements 16.

To accomplish the above function, there is secured beneath the floor boards 29 positioned between the angle irons 28 to the rear of the pedestal 19 a target contact disc 102. This disc 102 is connected to the angle irons 28 in any suitable manner, such as by spot welding, as shown in Fig. 2. The face of this disc 102 is provided with a plurality of scattered contact heads 103, which contact heads are connected in the electrical circuit, as shown in Fig. 11. Below the contact disc 102 and carried by a side wall of the pedestal 19 by means of right angle brackets 104 spaced apart and in confronting relation is a contact arm 105. This contact arm 105 is pivotally mounted between the brackets 104 on a supporting pin 106. To retain the arm 105 in an approximately verti-

cal position, there is employed a coil spring 107. This spring 107 embraces the pin 106 and has one free end thereof bearing upon the arm 105 as shown in Fig. 7. At the free end of this contact arm 105 there is provided a contact head 108. This contact head 108 is yieldably maintained against the disc 102 by the spring 107.

The function of the contact disc 102 and the contact arm 105 is as follows:

As the contact disc is fixedly supported to the movable cockpit 10, it is apparent that as the movable cockpit 10 is manually directed in a vertical or horizontal movement, the disc 102 will move therewith. As the disc 102 thus moves the contact arm 105, together with the contact head 108, will come into contact with the various scattered contact heads 103 of the disc 102.

Upon conditioning the device for operation an actuating switch 109 will complete an electrical circuit to the target element designated number 1, thus informing the operator that this is the target at which to aim the simulated gun. Thus, as the operator of the device aims the movable cockpit 10 and the simulated gun 14 at the first numbered and illuminated target element, the contact head 108 of the contact arm 105, will come into engagement with the contact head 103 of the contact disc 102, thus completing a circuit to the next succeeding target.

The circuit, as shown in Fig. 11, discloses a method whereby the target element 16, designated as number 1, will be illuminated upon the closing of the actuating switch 109. This target element will remain illuminated until the simulated gun has been successfully aimed therat. At this time the contact arm 105, together with its contact head 108, will come into contact with the properly designated contact head 103 of the contact disc 102, whereby the holding relay 101 will be energized. This relay actuates a three-pole switch. The energization of this relay 101 will break the contact of two of these poles and make contact on the third. When such action takes place, the circuit to the target element #1 is broken, while the circuit to the target element #2, through the conductors 99 and 100 is complete, thereby illuminating such target element #2. For each number of target elements, it is therefore clear that there must be a holding relay 101 which actuates a like three-pole switch as hereinabove described.

Thus, as the operator of the device aims the movable cockpit 10 and the simulated gun 14 at the first numbered target element, the contact head 108 of the contact arm 105, will come into engagement with the contact head 103 of the contact disc 102, thus completing the circuit to that particular target element.

It may be desired that this device be coin-controlled. In that event, in the electrical circuit, as shown in Fig. 11, the actuating switch 109 will be coin-controlled. To the coin-actuated switch 109, there will be incorporated in the electrical circuit a timing switch 110, thus permitting the operation of the device for a predetermined period of time.

The device will best operate when it is equipped with a cut-off switch 111, which switch is in the electrical circuit, shown in Fig. 12. It is desirable that this switch be closed at the end of the cycle of the timing switch 110. The purpose of this cut-out switch 111 is to open the valve #1 when the timing switch has completed its cycle. By opening the valve #1 at such time, any and all compressed air contained in the hose connec-

tions 51 will be forced into the valve #1, thus causing the nose 13 of the cockpit 10 to move in a downward direction, indicating to the operator that the operation of the device is at an end.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. An amusement game and target practicing apparatus comprising a movable simulated vehicle having a cockpit and a simulated gun carried by the nose of the vehicle and extending forwardly with respect to said cockpit, a target structure including a target area in spaced confronting relation with respect to the nose of said vehicle and substantially at right angles with respect thereto and having target elements in said area to be illuminated, means for supporting said vehicle for movement relative to the target structure, means for moving said vehicle relative to the target structure, means for illuminating said target elements including an electric circuit, a power source in said circuit, a plurality of contacts in said circuit and carried by and movable with said vehicle and each having circuit connection with a certain one of said target elements, and a flexible member having a contact element in confronting relation with respect to said plurality of contacts and adapted to engage a certain one of said contact elements upon movement of said vehicle and in accordance with the position of said vehicle with respect to said target structure and with the synchronization of the line of sight of said gun with said certain one of said target elements.

2. An amusement game and target practicing apparatus comprising a movable simulated vehicle having a cockpit and a simulated gun carried by the nose of said vehicle and extending forwardly with respect thereto, a target structure including a target area in spaced confronting relation with respect to the nose of the vehicle and substantially at right angles with respect thereto and having target elements in said area to be illuminated, means for supporting said vehicle for vertical tiltable movement and for axial rotation with respect to said target structure, means for vertically tilting said vehicle, means for axially rotating said vehicle, and means for illuminating said target elements including an electric circuit, a power source in said circuit, a plurality of juxtaposed contacts in said circuit and carried by and movable with said vehicle and each having circuit connection with a certain one of said target elements, and a flexible member having a contact element disposed in confronting relation with respect to said plurality of contacts and adapted to engage a certain one of said contacts in accordance with the position of the vehicle with respect to the target structure and with the synchronization of the line of sight of said gun with said certain one of said target elements.

3. An amusement game and target practicing apparatus comprising a movable simulated vehicle having a cockpit and a simulated gun carried by the nose of the vehicle and extending for-

wardly with respect to said cockpit, a target structure including a target area in spaced confronting relation with respect to the nose of said vehicle and substantially at right angles with respect thereto and having target elements in said area to be illuminated, means for supporting said vehicle for movement relative to the target structure, means for moving said vehicle relative to the target structure, means for illuminating said target elements including an electric circuit, a power source in said circuit, a plurality of contacts in said circuit and carried by and movable with said vehicle and each having circuit connection with a certain one of said target elements, and a flexible member having a contact element in confronting relation with respect to said plurality of contacts and adapted to engage a certain one of said contact elements upon movement of said vehicle and in accordance with the position of said vehicle with respect to said target structure and with the synchronization of the line of sight of said gun with said certain one of said target elements, and manually controlled means for said tilting and rotating means.

4. An amusement game and target practicing apparatus comprising a movable simulated vehicle having a cockpit and a simulated gun carried by the nose of said vehicle and extending forwardly with respect thereto, a target structure including a target area in spaced confronting relation with respect to the nose of the vehicle and substantially at right angles with respect thereto and having target elements in said area to be illuminated, means for supporting said vehicle for vertical tiltable movement and for axial rotation with respect to said target structure, means for vertically tilting said vehicle, means for axially rotating said vehicle, means for illuminating said target elements including an electric circuit, a power source in said circuit, a plurality of juxta-positioned contacts in said circuit and carried by and movable with said vehicle and each having circuit connection with a certain one of said target elements, and a flexible member having a contact element disposed in confronting relation with respect to said plurality of contacts and adapted to engage a certain one of said contact elements upon movement of said vehicle and in accordance with the position of said vehicle with respect to said target structure and with the synchronization of the line of sight of said gun with said certain one of said target elements, and manually controlled means for said moving means.

10 15 20 25 30 35 40 45

tacts and adapted to engage a certain one of said contacts in accordance with the position of the vehicle with respect to the target structure and with the synchronization of the line of sight of said gun with said certain one of said target elements, and manually controlled means for said tilting and rotating means.

5. An amusement game and target practicing apparatus comprising a movable simulated vehicle having a cockpit and a simulated gun carried by the nose of the vehicle and extending forwardly with respect to said cockpit, a target structure including a target area in spaced confronting relation with respect to the nose of said vehicle and substantially at right angles with respect thereto and having target elements in said area to be illuminated, means for supporting said vehicle for movement relative to the target structure, means for moving said vehicle relative to the target structure, means for successively illuminating said target elements including an electric circuit, a power source in said circuit, circuit holding means for each of said target elements in said circuit, a plurality of contacts in said circuit and carried by and movable with said vehicle and each having circuit connection with a certain one of said target elements, and a flexible member having a contact element in confronting relation with respect to said plurality of contacts and adapted to engage a certain one of said contact elements upon movement of said vehicle and in accordance with the position of said vehicle with respect to said target structure and with the synchronization of the line of sight of said gun with said certain one of said target elements.

JERRY C. KOCH.
